LARS M. THORSON AND KENNETH B. WARD, OF CHICAGO, ILLINOIS.

COMBINATION WARM-AIR CLEANER AND HEAT CONVERTER.

Application filed October 28, 1926. Serial No. 144,825.

Our invention relates to improvements in a combination warm air cleaner and heat converter of the type adapted for use in connection with warm air registers supplied with warm air from a furnace or other source; and the objects of our improvements are: first, to convert a portion of the convected heat, supplied by warm air from any source, to radiated heat; second, to increase the humidity of the warm air carrying the remaining unconverted convected heat; third, to clean the warm air; fourth, to deflect the warm air, carrying convected heat, in an approximately horizontal direction; fifth, to provide a warm air radiator, whereby radiated heat may be transmitted in all directions from a unit or device supplied with warm air; sixth, to provide means for extracting carbon monoxide gas in small quantities from warm air supplied by any source; seventh, to save a part of the fuel otherwise required; eighth, to improve the prophylactic quality of warm air supplied from any source; ninth, to conserve heat by insulating the back and any other part as desired; and tenth, to provide an effective means for preventing the smudging and rapid deterioration of interior decorating, wall paper, and other objects adjacent to warm air registers. These and other objects are attained by the means herein described and disclosed in the accompanying drawings.

One form of our invention is illustrated by way of example in the accompanying drawing, in which:

Fig. 1 is a perspective view of the entire device;

Fig. 2 is a vertical cross section of the entire device; and

Fig. 3 is a fragmental horizontal section through the heat collecting and radiating element, this view being taken on the line 3-3 of Fig. 2 and on a larger scale.

Although, for the purpose of illustrating a practical application of our device, we have shown it in Fig. 2 in association with a floor register 11, it will be understood that in practice our device is not to be confined to this particular use, but may be employed in connection with any suitable warm air outlet or any suitable structure for discharging or distributing warm air.

Our device in its preferred embodiment, comprises a box-like metal body or duct,

designated generally by the numeral 12, the same being provided at the front with a heat collecting and radiating element 13 and containing therein a water pan 14 and also a perforated wick fabric sheet 15. The body or duct 12 has a bottom inlet opening 16 adapted to come over the openings 17 of the warm air register 11, and a top outlet opening 18 at its front. The heat collecting and radiating element 13 is of serpentine formation, being bent inwardly and outwardly into a series of folds 19 to provide deep vertically extending inside pockets 20, and the opposing inside faces of the folds have projecting portions 21 which serve as means for delaying the up-going air currents so that the heat borne thereby may be transmitted to the folds for radiation. The series of pockets 20 are in open communication with the interior of the body or duct at their bottom ends 22, at their top ends 22' and at their interior sides 23. Brackets 24 provide supporting means for the water pan 14. The perforated wick fabric sheet 15 is stretched over a bar 25 in such a manner that its two lower edges 26 will be immersed in water 27 when the water pan contains water. Small bars 28 may be used to provide weights for holding down the edges 26. The perforated wick fabric sheet 15 may be of any absorbent material capable of raising water by capillary attraction.

The curved front piece 29 is a baffle used to cause warm air rising upwardly within the device and from the pockets to be deflected through the perforated wick fabric sheet 15. This baffle 29 is hinged at 30 to facilitate the placing and replacing of the water pan 14. The top 31 is hinged at the back edge 32 in order to permit the convenient refilling of the water pan by any convenient means.

Where the device is to be used in connection with a register located near a wall, the back 33 may be heat insulated by providing a thickness of cellular gypsum 34 or any other suitable heat insulating material.

The device is preferably constructed of sheet metal except as herein otherwise specified, but may be made of any other material possessing the requisite structural and physical properties. The device is preferably made of ornate design in order to harmonize with various kinds and types of furniture.

The device is prepared for use as follows: The water pan 14 is filled with water 27; and the perforated wick fabric sheet 15 is placed in the position shown in Fig. 2, so 5 that it will become moistened throughout by capillary attraction.

The device operates as follows: The warm air supplied from any suitable source enters through the inlet opening 16 and rises upwardly in the direction of the arrows 10 through the pockets 20 where the projecting portions 21 retard the rise of the air sufficiently to permit some of the heat borne thereby to be transferred to the metal radiating element 13 and hence dissipated 15 through the adjacent outside air. In this way a part of the convected heat will be absorbed and converted into radiated heat which will travel largely in horizontal directions and thus heat the adjacent objects. 20 Obviously, this operation cools the air carrying the remaining convected heat and since such air will not rise so rapidly, it can be more successfully deflected in a horizontal 25 direction. From the vertical pockets, the warm air passes through the perforated wick fabric sheets, being directed therethrough by the top baffle 29. Preferably and as shown, the wick fabric sheet is so 30 made or so positioned that the perforations 35 of its adjacent runs will be out of alignment. In passing through the perforated wick fabric sheet, the warm air is automatically cleaned and to some extent moistened 35 in case it happens to be dry. The cleaned air then rises and is deflected by the top 31 towards the front of the device where it is discharged into the room through the outlet opening 18 in an approximately horizontal 40 direction as indicated by the arrows.

A change in the location of the inlet opening 16 may be required to adapt the device for use in connection with baseboard or wall registers.

45 The perforated wick fabric sheet can be replaced easily whenever it requires cleaning. The water pan can be conveniently filled by lifting the top or cover 31 and adding the required water.

50 While we have shown and described only one form of our invention, it is to be understood that it is capable of many modifications. Changes, therefore in the construction and arrangement may be made without departing from the spirit and scope of the 55 invention as disclosed in the appended claims, in which it is our intention to claim all novelty inherent in our invention as broadly as possible in view of the prior art.

50 What we regard as new, and desire to secure by Letters Patent, is:

1. A device of the kind described comprising a duct body having an air inlet opening arranged to cover a warm air register, and 55 an outlet opening arranged to discharge

warm air in approximately horizontal directions; and a radiating element forming a wall of the duct body and provided with folds forming a series of air pockets between said openings.

70

2. A device of the kind described comprising a duct body having an air inlet opening arranged to cover a warm air register, and an air outlet opening; a radiating element forming a wall of the duct body and provided with folds forming a series of air pockets between said openings; and acute, heat collecting projections on said folds extending into said air pockets.

75

3. A device of the kind described comprising a duct body having air inlet and outlet openings; a radiating element forming a wall of the duct body and provided with folds forming a series of air pockets between said openings; and a moisture carrying sheet 80 pervious to air arranged in the path of the air between said pockets and the outlet opening.

85

4. A device of the kind described comprising a duct body having air inlet and outlet 90 openings; a radiating element forming a wall of the duct body and provided with folds forming a series of air pockets between said openings; heat collecting projections on said folds extending into said pockets; and a moisture carrying sheet pervious to air 95 arranged in the path of the air between said pockets and the outlet opening.

100

5. A device of the kind described comprising an upright duct body having a lower inlet opening and an upper outlet opening; a radiating element forming a wall of the duct body and having a series of jutting folds forming a series of air pockets upwardly extending along the passageway between said inlet and outlet openings; a water pan extending transversely of said pockets in the passageway between the inlet and outlet openings; and a perforated moisture carrying sheet extending into said pan and 110 arranged across the air path between said series of pockets and said outlet opening.

105

6. A device of the kind described comprising a duct body enclosing an up-going air passageway with a lower inlet opening 115 and an upper outlet opening; a radiating element forming a wall of the duct body below the outlet opening and having a series of jutting folds forming a series of air pockets opening into said passageway; a water pan partly closing said passageway adjacent said pockets; a baffle structure at the upper ends of said pockets; and a perforated moisture carrying sheet depending from said baffle structure and entering said 120 water pan.

125

7. In combination with a duct body enclosing an up-going air passageway, of a wall included in said body and having a series of folds extending into said passage- 130

way; a water pan obstructing said passageway opposite said folds; a baffle structure extending into said passageway and overhanging said folds; and a moisture carrying sheet pervious to air extending from within said water pan to said baffle structure whereby to moisten and clean the air passing from said folds into said passageway.

8. In combination, a duct body enclosing an air passageway containing a water pan, a perforated absorbent fabric, and a baffle supporting said fabric; said duct body having an inlet opening adapted to cover a warm air register, and an outlet opening; said perforated absorbent fabric having two opposite edges immersed in water in said pan, and arranged to form a plurality of moisture yielding dust collecting screens across said passageway; and said baffle extending across said duct, partly closing said passageway,

and arranged to compel warm air to pass through said screens.

9. In combination, a duct body enclosing an air passageway containing a water pan, a perforated wick fabric and supporting means therefor; said duct body having an inlet opening adapted to cover the openings of a warm air register, and an outlet opening; said wick fabric having one edge held within said water pan and arranged to form a dust arresting screen across said passageway; and a radiating element having heat collecting projections extending into said passageway and constructed of folds constituting outside parts of said duct body.

In testimony whereof, we have signed our names to this specification.

LARS M. THORSON.
KENNETH B. WARD.
